United States Patent Office.

W. G. RAOUL, OF INDEPENDENCE, LOUISIANA.

Letters Patent No. 99,350, dated February 1, 1870.

IMPROVEMENT IN GROOVING-MACHINE.

The Schedule referred to in these Letters Patent and making part of the same.

To all whom it may concern:

Be it known that I, W. G. RAOUL, of Independence, in the parish of Tangipahoa, and State of Louisiana, have invented a new and improved Gaining-Machine; and I do hereby declare that the following is a full, clear, and exact description thereof, which will enable others skilled in the art to make and use the same, reference being had to the accompanying drawings, forming part of this specification.

This invention relates to improvements in machines for cutting slots or gains in timber for framing, whereby it is designed to provide a simple and efficient machine for performing the work rapidly and cheaply, cutting the said gains at any required angle to the timber.

The invention consists in the arrangement of an improved adjustable rotary cutter, a vertically and horizontally-adjustable feeding-table, and clamping-devices for holding the work to be operated on, all as herein-after more fully specified.

Figure 1 represents a sectional elevation of my improved machine, taken on the line $x x$ of fig. 2.

Figure 2 represents a plan view of the same.

Similar letters of reference indicate corresponding parts.

A and B represent disks, arranged on a mandrel, C, one being fixed and the other being adjustable toward or from it.

These disks carry in their outer sides radial cutters, D, for cutting down the shoulders of the gains or recesses. They also carry between them flat cutters, E, for planing out the substance between the end cutters D. The said cutters E are held in grooves and brackets on the inner faces of the disks, pitched tangentially to a circumferential line between the periphery and the axis of the disks.

The brackets F and grooves for holding the cutters are applied alternately to each disk, so that the disks may be moved to or from each other, for narrower or wider gains, which may thus be cut by narrow tools, those of one disk lapsing those of the other.

G represents a feeding-table, placed on ways, and provided with a large central circular opening, in which

is placed an adjusting-ring, I, for holding the timber to be cut at any required angle to the cutting-tool, which works at the centre of this opening, and within this ring is another clamping-ring, K.

The table has an annular rebate, whereon the ring I rests, and a similar rebate in the latter supports the ring K.

The ring I may be turned to any position, and secured by a set-screw, L. It carries pins M, against which the timber N is clamped, for holding against the cutting-tool.

The ring K carries holding-dogs O, adjustable vertically, and provided with set-screws P. The timber Q is placed under these dogs, and the ring K is turned by the hand-lever R, so as to bring the timber up against the pins M, of the ring I, snugly, where it is thus held while being cut.

To vary the depth of the gains or grooves, the ways H, wherein the table moves to feed the timber up to the cutter, are made adjustable vertically, and an adjusting-frame, the two side-bars S of which have inclines T, working under the ways, is used, and it is provided with an adjusting-screw, U, for moving it to and fro, for raising or lowering the said ways.

The bearing V, of the mandrel of the cutter, is made adjustable, so that the mandrel may be readily removed and a mandrel carrying a saw substituted, to make the machine available for sawing-purposes.

Having thus described my invention, I claim as new, and desire to secure by Letters Patent—

1. The arrangement of disks A B, cutters D E, mandrel C, feeding-table G, and adjusting-devices S T, as and for the purpose specified.

2. The combination, with a feeding-table, G, of an adjusting-ring, I, and clamping-ring K, when arranged substantially as specified.

W. G. RAOUL.
